UNITED STATES PATENT OFFICE.

JOHN T. CORLEY, OF PROVIDENCE, RHODE ISLAND.

CLAMP FOR LAMP-BRACKETS.

1,187,044.

Specification of Letters Patent. Patented June 13, 1916.

Application filed February 4, 1914. Serial No. 816,467.

To all whom it may concern:

Be it known that I, JOHN T. CORLEY, a citizen of the United States, and resident of the city of Providence, in the county of Providence and State of Rhode Island, have invented certain new and useful Improvements in Clamps for Lamp-Brackets, of which the following is a specification.

This invention relates to tie rod clamps for lamp brackets for vehicles, and has for its object to provide this class of tie rod clamp comprising a body portion forming a socket for receiving the end of the tie rod, said body having means whereby it may be caused to grip or be clamped upon the tie rod and also providing a clamping member at the end of said socket for engaging and gripping one horn of the lamp bracket.

A further object of this invention is to set the horn clamp so that the axis of its clamping portion is at a right angle to that of the tie rod socket and to offset said clamp to the rear of the socket axis to facilitate the positioning of this clamping member upon the lamp forks of a certain type of automobile.

A further object of the invention is to provide means in the socket member whereby the tie rod may be adjusted endwise to accommodate the varying distances between lamp brackets on different vehicles.

With these and other objects in view, the invention consists of certain novel features of construction, as will be more fully described and particularly pointed out in the appended claims.

Of the accompanying drawings: Figure 1— is a front elevation showing my improved clamping device in position on the lamp brackets of the vehicle to which it is adapted to be applied. Fig. 2— is a top view showing a portion of the vehicle hood and the relative position of my clamping device as attached to the lamp forks showing the arrangement whereby the offsetting of the clamp is necessary. Fig. 3— is a front elevation of the clamp member. Fig. 4— is a plan view of the clamp member showing the axis of the fork clamp offset to the rear of the axis of the rod socket and showing a portion of the rod adjustably retained in its socket. Fig. 5— is a modification showing the rod socket as threaded whereby the rod may be adjusted endwise therein, also showing a forked outer end adapted to engage and be bound to the horn of the lamp

bracket. Fig. 6— is an end view of the modified form of clamp. Fig. 7— is a detail of the tie rod which is provided with right and left hand threads at its opposite ends whereby rotating of the same in its clamps will extend or shorten its operating length.

Referring to the drawing, 10 designates the body or socket portion of the clamp member which has an elongated body split at 11 on one side and provided with a pair of ears 12 through one of which a screw 13 passes, and is threaded into the opposite ear. The bore of this socket member is of a size to receive a tie rod 14 of the required diameter. This socket member has a clamping member 15 extending directly outward from the end thereof, the same being provided with a cap 16, which is connected thereto by means of binding screws 17 and 18. The cap 75 and the clamp member between them are provided with a bore or hole 19 whose axis is set at a right angle to that of the socket member, and said bore is offset to the rear of the axis of said socket member for the express purpose of receiving and accommodating the lamp bracket horn 20, see Fig. 2, which is set back substantially in line with the front face of the radiator 21 of the machine.

In positioning my improved device upon a pair of lamp brackets it is only necessary to place one of the clamps on either end of the tie rod 14, then remove the caps 6 of the clamping members, position the same on their respective horns, then screw on the 90 caps. The hole through the clamp is left a trifle small so that when the screws are set up the clamp will be tightly bound upon the horn. The opposite lamp brackets are now pressed toward each other slightly to 95 place them under tension, and the binding screws 13—13 are set up in the different sockets upon the tie rod holding the whole firm and rigid against shaking or rattling.

In some instances instead of providing a 100 cap to the clamping member, as illustrated in Fig. 4, I form an outwardly extending clamp portion provided with a U-shaped yoke, preferably turned at right angles to the axis of the socket, which yoke is adapted 105 to be passed around the horn 20 of the lamp bracket and a bolt 22 is passed through the ends 23 of the yoke so that when the nut 24 is set up it will tighten the yoke about the horn and bind the same firmly in position 110 thereon. The space between the inner end of the yoke and the bolt 22 practically forms

a bore at right angles to the axis of the socket. The socket portion of this clamping member is shown as being somewhat elongated and internally threaded as at 25. 5 The same is also split as at 26, see Fig. 6, through one side thereof and provided with two pairs of ears 27 and 28 which are adapted to be drawn together by means of screws 29 and 30 to bind the rod therein. The rod 10 31 shown in Fig. 7 is provided with right and left hand threads 32 and 33 at its opposite ends and adapted to be screwed into these threaded sockets, whereby by rotating the rod in the sockets the working length of 15 the device is adjusted and regulated to suit the different vehicles to which it is applied, and after the device has been positioned on the horns of the different lamp brackets, the rod is rotated until sufficient tension has 20 been applied to these brackets and then by setting up the screws 29 and 30 the sockets are bound firmly in position to the rod holding the same firmly and securely therein.

The device as will be seen is designed more 25 particularly to be applied to a particular type of car and as it is found that there is a slight variation in the position of the brackets in the different cars it is absolutely necessary to provide means whereby a lengthwise 30 adjustment of the tie rod in its socket may be obtained, whether it is to slide lengthwise

in the socket, as illustrated in Fig. 4, or be threaded thereinto for adjustment as illustrated in Fig. 5.

I claim:

1. The combination with a lamp bracket tie rod, of a clamp member at either end thereof, each of said members having a socket portion in which the rod end adjustably fits, means in the socket member for binding the rod ends, each of said socket members being provided with a clamping member for engaging and clamping a horn of the lamp brackets. 40

2. The combination with a lamp bracket tie rod, of a clamp member at either end thereof, each of said members having a socket portion in which the rod end adjustably fits, means in the socket member for binding the rod ends, each of said socket members being provided with a clamping member for engaging and clamping a horn of the lamp brackets, the axis of said clamps being set at right angles to that of the rod and offset to the rear thereof. 45

55 In testimony whereof I affix my signature in presence of two witnesses.

JOHN T. CORLEY.
